(57) **CLAIM**

The ornamental design for a beverage container, as shown and described.

DESCRIPTION

FIG. 1 is a perspective view of a beverage container showing my new design;

FIG. 2 is a front view thereof, the left side, right side and rear views being the same, excluding the thread element on the pour spout of the beverage container;

FIG. 3 is a top plan view thereof; and,

FIG. 4 is a bottom plan view thereof.

The broken lines in the drawings illustrate the portions of the beverage container that form no part of the claim.
